UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

ELEVATING MECHANISM OF HEAVY GUNS.

1,291,775.

Specification of Letters Patent. Patented Jan. 21, 1919.

Application filed May 15, 1915. Serial No. 28,495.

To all whom it may concern:

Be it known that we, Sir ARTHUR TREVOR DAWSON, Knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to the Elevating Mechanism of Heavy Guns, of which the following is a specification.

This invention relates to elevating mechanism of the kind in which two hydraulic presses or cylinders are employed, the ends of the rams or piston rods of these presses being preferably attached to a slipper connected by links to the elevating bracket or trunnion arm.

According to this invention we provide means whereby the presses can be operated either by liquid under pressure obtained from the hydraulic mains or by liquid supplied by a variable delivery pump, without its being necessary to drain the presses or cylinders in changing from one system to the other.

In order that the said invention may be clearly understood and readily carried into effect we will describe the same more fully with reference to the accompanying drawing, which is a sectional side elevation showing in a more or less diagrammatic manner the constructional form of the invention.

A, A^x are the two elevating presses and a, a^x are their rams or piston rods. B is the slipper to which the rams or piston rods are attached, and b is one of the links connecting the slipper to the elevating bracket or trunnion arm B'. C represents the control valve of the hydraulic system and D represents the variable delivery pump driven by an electric motor D^x.

In the example shown the cylinders A, A^x are oppositely arranged and their inner ends are connected by pipes a', a'^x, to the control valve C while the outer ends are connected by pipes d', d'^x to the variable delivery pump D. The pipe a' has a stop valve a² and the pipe a'^x has a similar valve a^{2x}; these two pipes are connected through another stop valve A'. For purposes of distinction we term the last mentioned valve

the main stop valve and the other two stop valves the secondary stop valves. A similar arrangement of main and secondary stop valves (D', d², d^{2x}) is arranged between the pipes d', d'^x and between the variable delivery pump and the cylinders. When 55 the hydraulic system of elevating is employed, the main stop valve A' is closed and the secondary stop valves d², d^{2x} appertaining to the variable delivery pump are also closed, the other valves remaining open; 60 the liquid (usually oil) in the outer ends of the cylinders A, A^x is therefore caused to pass from one cylinder to the other during the hydraulic elevation of the gun. Conversely when pressure fluid from the variable delivery pump D is to be employed for 65 elevating the gun, the main stop valve D' appertaining to this pump is closed and the secondary valves appertaining to the hydraulic system are also closed (the other 70 valves remaining open) so that the fluid in the inner ends of the cylinders is caused to pass from one cylinder to the other during the elevation of the gun by the pressure fluid supplied by the pump D. 75

It is to be understood that any other suitable arrangement of stop valves for obtaining the above mentioned results may be employed.

What we claim and desire to secure by 85 Letters Patent of the United States is:—

1. In the elevating mechanism of ordnance, the combination with two pressure fluid elevating presses, of a variable delivery pump adapted to supply fluid under 90 pressure to said presses, a pressure fluid main also adapted to supply fluid under pressure to said presses and means whereby pressure fluid obtained from either of said sources can be used for operating said 95 presses without its being necessary to empty them of the liquid obtained from the other source.

2. In the elevating mechanism of ordnance, the combination with two pressure fluid elevating cylinders and their piston rods, of a variable delivery pump adapted to supply fluid under pressure to each of said cylinders, a pressure fluid main also adapted to supply fluid under pressure to 100 each of said cylinders and means whereby pressure fluid obtained from either of said supplies can be used for operating said pis- 105

ton rods without its being necessary to empty the cylinders of the pressure fluid obtained from the other supply.

3. In the elevating mechanism of ordnance, the combination with two pressure fluid elevating cylinders and their piston rods, of a variable delivery pump adapted to supply fluid under pressure to and to exhaust the fluid from one end of each of said cylinders, a pressure fluid main and an exhaust main adapted to supply fluid under pressure to and to exhaust the fluid from the other end of each cylinder, and stop valves for opening communications between one of said pair of cylinder ends and closing communication between them and the source of supply when the other pair of cylinder ends is in use.
4. In the elevating mechanism of ordnance, the combination with the elevating bracket of the gun and two hydraulic presses operating upon said elevating bracket of a variable delivery pump adapted to supply liquid under pressure to said presses, a hydraulic main also adapted to supply fluid under pressure to said presses and means whereby liquid obtained from either of said supplies can be used for operating said presses without its being necessary to empty them of the liquid obtained from the other supply.

5. In the elevating mechanism of ordnance, the combination with the elevating bracket of the gun and two oppositely arranged hydraulic cylinders whose piston rods operate upon said elevating bracket, of a variable delivery pump adapted to supply liquid under pressure to said presses, a hydraulic main also adapted to supply liquid under pressure to said presses and

means whereby liquid obtained from either of said supplies can be used for operating said presses without its being necessary to empty the presses of the liquid obtained from the other supply.

6. In the elevating mechanism of ordnance, the combination with the elevating bracket of the gun and two oppositely arranged hydraulic cylinders whose piston rods operate upon said elevating bracket, of a variable delivery pump adapted to supply liquid under pressure to each of said cylinders, a hydraulic main also adapted to supply liquid under pressure to each cylinder and means whereby liquid obtained from either of said supplies can be used for operating said piston rods without its being necessary to empty the cylinders of the liquid obtained from the other supply.

7. In the elevating mechanism of ordnance, the combination with the elevating bracket of the gun and two oppositely arranged hydraulic cylinders whose piston rods operate upon said elevating bracket, of a variable delivery pump adapted to supply liquid under pressure to and to exhaust the liquid from one end of each of said cylinders, a hydraulic main and an exhaust main adapted to supply liquid under pressure to and to exhaust the liquid from the other end of each cylinder and stop valves for opening communication between one of said pair of cylinder ends and closing communication between them and the source of supply when the other pair of cylinder ends is in use.

In testimony whereof we affix our signatures.

ARTHUR TREVOR DAWSON.

JAMES HORNE.
